(57) **CLAIM**

The ornamental design for a car floor mat set, as shown and described.

DESCRIPTION

FIG. 1 is a first perspective view of a first element of a car floor mat set showing my new design;

FIG. 2 is a second perspective view of the first element thereof;

FIG. 3 is a front view of the first element thereof;

FIG. 4 is a back view of the first element thereof;

FIG. 5 is a left side view of the first element thereof;

FIG. 6 is a right side view of the first element thereof;

FIG. 7 is a top view of the first element thereof;

FIG. 8 is a bottom view of the first element thereof;

FIG. 9 is a first perspective view of a second element of a car floor mat set showing my new design;

FIG. 10 is a second perspective view of the second element thereof;

FIG. 11 is a front view of the second element thereof;

FIG. 12 is a back view of the second element thereof;

FIG. 13 is a left side view of the second element thereof;

FIG. 14 is a right side view of the second element thereof;

FIG. 15 is a top view of the second element thereof;

FIG. 16 is a bottom view of the second element thereof;

FIG. 17 is a first perspective view of a third element of a car floor mat set showing my new design;

FIG. 18 is a second perspective view of the third element thereof;

FIG. 19 is a front view of the third element thereof;

FIG. 20 is a back view of the third element thereof;

FIG. 21 is a left side view of the third element thereof;

FIG. 22 is a right side view of the third element thereof;

FIG. 23 is a top view of the third element thereof;

FIG. 24 is a bottom view of the third element thereof; and,

FIG. 25 is a combination view of the first element, the second element and the third element of the car floor mat set thereof.

The broken lines shown in the drawings depict portions of the car floor mat set that form no part of the claimed design.
